DENTAL INSTRUMENT HOLDER

George N. Seifert, Kenmore, N. Y.

Application March 30, 1956, Serial No. 40,854

Term of patent 14 years

(Cl. D80—9)

FIG. 2.

Figure 1 is a perspective view of a dental instrument holder, showing my new design;

Figure 2 is an enlarged vertical sectional view taken substantially on line 2—2 of Figure 1; and

Figure 3 is an enlarged top plan view thereof.

I claim:

The ornamental design for a dental instrument holder, as shown and described.
